DESIGN FOR A HELICOPTER

Edward F. Katzenberger and Michael E. Gluhareff, Bridgeport, Conn., assignors to United Aircraft Corporation, East Hartford, Conn., a corporation of Delaware

Application September 24, 1946, Serial No. 133,532

Term of patent 7 years

(Cl. D71—1)

To all whom it may concern:

Be it known that we, Edward F. Katzenberger, a citizen of the United States, residing at 10 Washington Avenue, Bridgeport, in the county of Fairfield and State of Connecticut, and Michael E. Gluhareff, a citizen of the United States, residing at 579 Clinton Avenue, Bridgeport, in the county of Fairfield and State of Connecticut, have invented a new, original, and ornamental Design for Helicopter, of which the following is a specification, reference being had to the accompanying drawing, forming a part thereof.

Fig. 1 is a top plan view of a helicopter, showing our new design.

Fig. 2 is a side elevational view.

Fig. 3 is a front elevational view.

Fig. 4 is a perspective view.

Certain of the rotor blades have been shown only partially because they are identical to those blades shown in full.

We claim:

The ornamental design for a helicopter, substantially as shown.

EDWARD F. KATZENBERGER.
MICHAEL E. GLUHAREFF.
